UNITED STATES PATENT OFFICE.

EUGENE FRANK SCHOELL, OF NEW BRITAIN, CONNECTICUT, ASSIGNOR, BY MESNE ASSIGNMENTS, TO THE METAL SPECIALTY COMPANY, OF NEW BRITAIN, CONNECTICUT, A CORPORATION.

TOP.

1,253,195.

Specification of Letters Patent.

Patented Jan. 8, 1918.

Application filed December 28, 1916. Serial No. 139,262.

To all whom it may concern:

Be it known that I, EUGENE FRANK SCHOELL, a citizen of the United States, residing at New Britain, in the county of 5 Hartford and State of Connecticut, have invented certain new and useful Improvements in Tops, of which the following is a specification.

My invention relates to improvements in 10 tops, and the object of my improvement is to produce a top of the spinning type that is provided with spring winding means and that is complete and self-contained in the form of a unitary structure, being without 15 separable or loose parts.

In the accompanying drawing:

Figure 1 is a side elevation of my improved top.

Fig. 2 is a plan view of the same.

20 Fig. 3 is a sectional view on the line $\alpha-\alpha$ of Fig. 2.

Fig. 4 is a similar view of the upper part of the same with the parts in the released position.

25 Fig. 5 is a bottom view of the inner side of the cover.

Fig. 6 is a plan view of the blank for the bridge.

30 Fig. 7 is a sectional view of a modification of my top.

Fig. 8 is an edge view of the shaft shown in Fig. 7.

Fig. 9 is a sectional view of another modification of my top.

35 Fig. 10 is a plan view of the blank for the barrel and bridge member shown in Fig. 9.

Fig. 11 is a fragmentary sectional view on an enlarged scale, showing certain parts shown in Fig. 9 and in a different position.

40 Fig. 12 is a similar view, with the parts turned 90 degrees from the position shown in Fig. 11.

Fig. 13 is a plan view of the blank for the head or handle shown in Figs. 9, 10, 11, 45 and 12.

My improved top comprises a shell-like casing 10 having the exterior form in conformity to the usual form for spinning tops, comprising a tapered lower portion terminating in the tip 11 and a dome shaped upper portion and has at the upper end an upwardly projecting stem 12 terminating in a circular flat head 13, and within the casing 10 is housed mechanism for winding the top 50 by turning the head 13 and which mecha-

nism serves to operate the top and set the same in rotation or spinning by momentarily depressing the head 13 while the tip 11 is resting on the table or other support.

The casing 10 is made of sheet material 60 and is composed of two parts comprising the lower part 14 having the tapered side walls and provided with the tip 11 at the lower end, and the upper part 15 having the dome shape, and provided in the top end with the 65 hole 16 for the stem 12, the said parts having overlapping edges as shown at 17 and being locked in place in some suitable manner as by means of a set of lugs 18 formed by indenting the material of one part engaged with holes 19 in the mating part, the two parts 14 and 15 when united as described forming a unitary casing structure.

The stem 12 serves as a shaft for the casing 10, the hole 16 serving as the upper bearing therefor, the said shaft 12 extending downwardly through the body portion of the casing 10 and passing through a lower bearing 20 in the form of a hole in a bridge 21 that extends across the lower portion of 80 the casing at a position appreciably above the tip 11.

The bridge 21 consists of a piece of sheet material, comprising a body portion of suitable length to form a bearing platform for 85 the lower end of the spring 22 and having the bearing hole 20, and having the end portions 23, turned downwardly and provided at the tip ends with prongs 24 that are entered through holes 25 in the side 90 walls of the lower part 14 and which prongs 24 are of suitable length to be bent inwardly against the adjacent opposed portion 26 of the side wall, which portion 26 is appreciably tapered, whereby the bridge 21 is 95 positively secured in position in the casing.

The spring 22 is formed of wire, of helical form and incloses the shaft 12, the lower end of the body or coil portion resting on the platform 21 as mentioned, the wire material 100 27 at the lower end being extended from the spring body, and positively secured to the bridge 21 in some proper manner, as by being wound around the same, as shown.

The upper end 30 of the spring 22 is secured to the shaft 12 in some suitable manner, as by being passed through a hole in the same as shown.

As described, one end of the spring 22 is secured to the casing 10 and the other to the 110

shaft 12, so that by turning the shaft 12 relatively to the casing 11 the spring is wound up.

The spring 22 while serving as the winding spring for winding the top serves also as a ratchet spring for operating ratchet mechanism to be described, by which the control of the operation of the top is effected.

10 The said ratchet mechanism is adapted to permit winding the spring freely in one direction but tends to prevent return movement.

One method of construction of the said 15 ratchet mechanism, as shown, comprises a set of teeth 31 on the casing, and a diametral pin 32 provided on the said shaft 19.

That is to say, the teeth 31 are provided 20 on the under side of the top wall of the upper part 15 of the casing 10 and the pin 32 is held in bearing engagement with the said top wall by the spring 22, which is set so as to tend to open endwise, and operates as a compression spring, the projecting ends of 25 the pin 32 engaging with one or more of the teeth 31.

The teeth 31 are formed integrally with 30 the top wall and of saw tooth form, by the combination of a longitudinal or curved slit 33 and a short cross slit 34, the material severed by the said slits being turned downwardly to form the downwardly projecting ratchet teeth 31. As shown there are four teeth 31.

35 As described the pin 32 by engaging with the upper wall of the casing serves as a stop to limit the upward movement of the shaft, the said pin 32 thus serving as a stop for limiting movement of the shaft as well as a pawl to limit relative rotative movement.

40 Thus as described the head 13 is normally held in the elevated position, the position being determined by the engagement of the pin with the upper wall of the casing.

45 In this position the head may be turned to wind the spring, the unwinding thereof being prevented by the ratchet and pawl mechanism.

To set the top spinning the top is held 50 vertically, the head being engaged by the palm of the hand, the tip resting on the table or other support. By momentarily depressing the head with the top in the position described, the ratchet mechanism is 55 released, the top being thus free to turn relatively to the shaft, and the spring immediately imparts rotative movement to the top, and as the head is released by removing the hand the head is returned to normal 60 position and the entire top structure, including the head and stem, rotates by reason of the impulse imparted by the spring.

65 My improved top as described is complete and self-contained, having means for effecting the winding and for effecting the

release of the spring after being wound and thus effecting the spinning, and the top structure has all parts permanently connected, without any removable or separate parts.

The modification shown in Fig. 7 involves special features of construction. Thus the shaft 12^a is made of heavy sheet material, the pawl and stop pin 32 is replaced by arms 32^a integral with the said 75 shaft 12^a, and the tip or peg 11^a is formed integral with the lower part 14^a. The operation is similar to that of the style shown in Fig. 1.

In the modification shown in Figs. 9 to 80 11 there is a barrel 35 that serves as a core for the body of the spring 22^b, and the shaft 12^b is short, terminating at the lower end in an extension 49 that is entered into the upper end of the barrel 35.

I prefer to incorporate the barrel 35 with the bridge 22^b as shown, the same being formed from the blank as shown in Fig. 10. The said blank is rectangular in form, the upper portion 36 being adapted to be coiled 90 around in cylindrical form to form the barrel 35 and the lower part being divided by a longitudinal slit 37 into two bridge arms 38 that are bent outwardly laterally, in opposite direction, so as to combine to form the 95 bridge 21^b, and the supporting devices therefor, comprising the downwardly projecting end portions 23^b and the prongs 24^b at the extreme lower ends. The body portion 36 is of suitable length to receive the coil or 100 body portion of the spring 22^b, extends axially along the major part of the interior portion of the top structure, terminating a sufficient distance from the roof to provide for operatively housing the shaft 12^b and 105 connected parts, within the upper portion of the top structure.

The shaft 12^b is part of a moving member 39 on which the head or handle 13^b is mounted.

The said moving member 39 is formed of heavy sheet material, comprising a body portion having a pair of laterally directed wings 40, a shaft member 41 extending upwardly from the said body portion to form 115 the upper end of the shaft 12^b which passes through the roof of the top and to which the head 13^b is connected, and the extension 49 extending downwardly into the upper end of the barrel 35 and serving as the lower 120 shaft member, being rotatively and slidably engaged with the said upper end of the barrel 35.

The wings 40 have each an upwardly extending lug 32^b that serves as a pawl in co-operation with the ratchet teeth 31^b, and also as a longitudinal stop to limit the upward movement of the shaft 12^b and also have a downwardly directed lug 42 that overhangs the barrel 35. One of the said 130

downwardly directed lugs 42 has a hole 43 for the end of the spring 22^b, the other of the said lugs 42 being provided for the purposes of balancing the effect of the mating lug when the top is spinning.

The end of the upper shaft member 41 is reduced on two opposite sides to form shoulders 44 for the corresponding walls in the opening in the head 13^b. On the two intermediate sides there are wings 45 in bearing engagement therewith formed by slitting the material of the head 13^b, and turning the said wings 45 downwardly. The slitting of the said material comprises a pair of short parallel slits 46 cross-connected by an intermediate slit 47.

The barrel 35 serves as a guide for the spring 22^b, preventing distortion thereof, the operation of the top generally being similar for all of the different styles shown.

In some cases I may provide a small spring 48 between the roof of the top and the head 13^b to assist the main spring 22^b in holding the ratchet members in engagement.

I claim as my invention:—

1. A top comprising a shell-like body having a tip at the lower end, a shaft rotatably and slidably housed in the said body and extending upwardly through the upper end thereof, a spring within the said body connected by one end to the said body and by the other end to the said shaft, ratchet and pawl mechanism for checking the unwinding of the said spring and the said mechanism comprising a set of ratchet teeth, integral with the upper wall portion of the said body.

2. A top comprising a shell-like body having a tip at the lower end, a shaft rotatably and slidably housed in the said body and extending upwardly through the upper end thereof, a spring within the said body, and connected by one end to the said body

and by the other end to the said shaft, suitably to be wound by turning the said shaft relatively to the said body, ratchet and pawl mechanism for checking the unwinding of the said spring, and the said mechanism comprising a set of teeth integral with the said body and an arm extending radially from the said shaft.

3. In a top comprising a shell-like body and a shaft, a spring housed within the said body, and connected by one end to the said shaft, the other end of the said spring being supported by the said body and also connected to the said body, and the support for the said other end of the spring comprising a bridge extending across the said body, having means for receiving the lower end of the said shaft, and provided at the ends with means for being connected with the side walls of the said body.

4. A top comprising a shell-like body having a tip at the lower end, a shaft rotatively and slidably mounted in the said body and having the upper end extending upwardly through the said body and provided with a disk-like handle, a main spring operatively connecting the said body and shaft for effecting alternative winding and spinning movements, and an auxiliary spring positioned between the said handle and the upper wall portion of the said body tending to lift the said shaft relatively to the said body, an arm on the said shaft coöperating with the upper wall portion of the said body for limiting the upward movement of the said shaft, and the said upper wall portion having teeth for coöperating with the said arm for checking rotative movement of the said shaft.

EUGENE FRANK SCHOELL.
